CLAIM

The ornamental design for a portable monitor, as shown and described.

DESCRIPTION

FIG. 1 is a perspective view of a portable monitor showing the new design;

FIG. 2 is another perspective view thereof;

FIG. 3 is a perspective view of the portable monitor with its stand extended;

FIG. 4 is a front elevation view of the portable monitor with its stand collapsed;

FIG. 5 is a back elevation view thereof;

FIG. 6 is a left-side view thereof;

FIG. 7 is a right-side view thereof;

FIG. 8 is a top plan view thereof;

FIG. 9 is a bottom plan view thereof;

FIG. 10 is an enlarged view of the encircled portion in FIG. 7; and,

FIG. 11 is an enlarged view of the encircled portion in FIG. 8.

The dash-dash broken lines depict portions of the portable monitor that form no part of the claimed design.

The dash-dot broken lines in FIGS. 7, 8, 10 and 11 represent the extents of the enlarged detail views and form no part of the claimed design.

1 Claim, 11 Drawing Sheets
